UNITED STATES PATENT OFFICE.

JAY D. PARKINSON, OF LAPORTE, INDIANA.

GATE-HINGE.

SPECIFICATION forming part of Letters Patent No. 746,142, dated December 8, 1903.

Application filed April 8, 1903. Serial No. 151,654. (No model.)

To all whom it may concern:

Be it known that I, JAY D. PARKINSON, a citizen of the United States, residing at Laporte, in the county of Laporte and State of Indiana, have invented a new and useful Gate-Hinge, of which the following is a specification.

My invention relates to hinges, being especially directed to gate-hinges, and has for its objects to produce a device of this character which will be simple of construction, efficient in operation, and one in which the friction will be reduced to a minimum.

With these and other objects in view the invention comprises the novel details of construction and combination of parts more fully hereinafter described.

In the accompanying drawings, Figure 1 is a perspective view of a gate having my improvements applied thereto. Fig. 2 is a side elevation on an enlarged scale.

Referring to the drawings, 1 indicates the terminal fence-post, which is situated at one side of the road or gateway and constitutes the hinge-post of the gate, and 3 is a gate comprising end post 4, upper and lower rails or bars, and diagonal braces 6. These parts may all be of the usual or any desired form, construction, and material, inasmuch as they constitute no part of my invention.

In accordance with my invention the gate 3 is pivoted or hinged for swinging movement in a horizontal plane to the post 1 by means of a hinge-rod 7, which extends downward through upper and lower hinge members 8 and 9, secured to the end post 4 of the gate and through upper and lower hinge members 10 and 11, carried by the post 1. The hinge members 8 9 are preferably in the form of flat metal castings having lateral ears 12, bolted or otherwise secured to the post 4, and rearwardly-extending portions centrally perforated for the reception of the rod 7. The upper and lower hinge members 10 11, which are carried by the post 1, consist preferably of ordinary screw-eyebolts tapped horizontally into the post with their eye portions projecting laterally from the post in position to receive the rod 7. The rod 7 extends loosely through the hinge members 10 11, but is fixedly connected with the hinge members 8 9 by means of set-screws 13, whereby the rod

will, when rotated in the manner hereinafter described, serve to swing the gate to an open or closed position.

14 and 15 indicate, respectively, upper and lower blocks mounted upon the rod 7 for adjustment longitudinally thereof and adapted to be fixed in their adjusted positions upon the rod by means of set-screws 16. The upper member 14 is mounted upon the rod beneath the hinge member 10, while the lower member 15 is situated between the hinge members 9 and 11. In this connection attention is directed to the fact that the gate may be adjusted vertically upon the rod 7 by releasing the set-screws 13 and after having been brought to the proper adjustment may be fixed in such position by manipulating said screws to again engage the rod and that the rod itself may be adjusted bodily in a vertical plane, carrying with it the gate 3, and be maintained in such adjusted position by the lower block 15, while the upper member 14 can at the same time be properly adjusted for engagement beneath the hinge member 10 to prevent escape of the lower end of the rod from the hinge member 11. Thus it will be seen by reference to Fig. 2 that when the parts are properly arranged relatively the entire weight of the gate in a vertical plane will be sustained by the lower member 15 bearing upon the lower hinge member 11 and that the only frictional contact of the parts will be between the member 15 and the hinge member 11, thus reducing such friction to a minimum, prolonging the life of the various elements of the hinge mechanism, and insuring easy movement of the gate.

The pivoting-rod 7 is extended at its upper end at an angle to the rod to form a substantially horizontal arm 17, which extends rearward of the gate in parallel relation thereto and is provided at its outer end with an eye 18, adapted for the attachment of suitable gate-operating ropes, (not shown,) which are extended to and operated from opposite sides of the gate in the well-known manner and which serve when manipulated to swing the arm in a horizontal plane, thus moving the gate, which is fixedly associated with the rod, to an open or closed position, as will be readily understood.

From the foregoing it will be seen that I

produce a simple and efficient mechanism which is admirably adapted for the attainment of the ends in view and one in which the surfaces of but two of the movable parts 5 contact one with the other, thus reducing the friction to a minimum and insuring the gate moving with ease and freedom, and in attaining these ends it is to be understood that I do not limit myself to the precise details 10 herein shown and described, inasmuch as minor changes may be made therein without departing from the spirit or scope of my invention.

Having thus described my invention, what 15 I claim is—

In a device of the class described, the combination with a hinge-post, of hinge mem-

bers attached thereto, a gate, hinge members attached thereto, a vertical pivoting-rod extending through the hinge members, means 20 for fixing the hinge members of the gate to the rod, said means being operable to permit vertical relative adjustment of the gate and rod, a block adjustably connected with the rod beneath one pair of the hinge members, 25 and a block adjustably connected with the rod between the other pair of hinge members.

In testimony that I claim the foregoing as my own I have hereto affixed my signature in the presence of two witnesses.

JAY D. PARKINSON.
